DESIGN FOR A COMBINED BEVERAGE MEASURE AND DISPENSER

Robert Lee Humbard, Palm Springs, and
Richard J. Burke, Altadena, Calif.

Application August 13, 1936, Serial No. 64,401

Term of patent 14 years

To all whom it may concern:

Be it known that we, Robert Lee Humbard, a citizen of the United States, residing at Palm Springs, California, in the county of Riverside and State of California, and Richard J. Burke, a subject of the King of Great Britain who has declared his intention of becoming a citizen of the United States, residing at Altadena, Los Angeles county, California, have invented a new, original, and ornamental Design for a Combined Beverage Measure and Dispenser, of which the following is a specification, reference being had to the accompanying drawing, forming a part thereof.

Referring to the drawing:

Figure 1 is a view in side elevation of a combined beverage measure and dispenser, showing our new design.

Figure 2 is a top plan view of the article illustrated in Figure 1.

We claim:

The ornamental design for a combined beverage measure and dispenser, as shown.

ROBERT LEE HUMBARD.
RICHARD J. BURKE.
